UNITED STATES PATENT OFFICE

106,808

DESIGN FOR AN UPPER BOWL COVER FOR A COFFEE BREWER OR SIMILAR ARTICLE

Edward Perlman, Niles Center, Ill.

Application August 11, 1937, Serial No. 71,009

Term of patent 7 years

To all whom it may concern:

Be it known that I, Edward Perlman, a citizen of the United States and a resident of Niles Center, in the county of Cook and State of Illinois, have invented a new, original, and ornamental Design for an Upper Bowl Cover for a Coffee Brewer or Similar Article, of which the following is a specification, reference being had to the accompanying drawing, forming a part thereof.

In the drawing:

Fig. 1 is a top plan view of the article showing my design; and

Fig. 2 is a side elevational view thereof.

I claim:

The ornamental design for an upper bowl cover for a coffee brewer or similar article as shown.

EDWARD PERLMAN.
